DESIGN.

H. C. BASCOM & F. RITCHIE.
HEATING STOVE.

No. 20,423.

Patented Dec. 23, 1890.

UNITED STATES PATENT OFFICE.

H. CLAY BASCOM, OF LANSINGBURG, AND FRANCIS RITCHIE, OF TROY,
NEW YORK.

DESIGN FOR A HEATING-STOVE.

SPECIFICATION forming part of Design No. 20,423, dated December 23, 1890.

Application filed September 8, 1890. Serial No. 364,353. Term of patent 3½ years.

To all whom it may concern:

Be it known that we, HENRY CLAY BASCOM and FRANCIS RITCHIE, citizens of the United States, residing, the said BASCOM at the village of Lansingburg, county of Rensselaer, and State of New York, and the said RITCHIE at the city of Troy, in said county and State, have invented and produced a new and original Design for Heating-Stoves, of which the following is a specification, reference being had to the accompanying drawing, forming part thereof, and consisting of a single figure, affording a view in perspective of our newly-designed stove.

15 The leading features of our new design consist in the novel configuration and ornamentation.

Our newly-designed stove comprises a cylindrical combustion-chamber A, separated 20 by the circular flange A² from a lower upwardly-flaring fire-pot A³, having a corrugated exterior and surmounted by a circular top A⁴. The combustion-chamber is provided with the doors A⁵ and A⁶, one above and contiguous to 25 the other. The corrugations entirely surround the fire-box and extend vertically the whole length of the same to the circular flange A², which has plain unornamented surfaces. The fire-pot rests upon the circular base A⁷, which 30 separates it from the circular ash-pit A⁸, and the legs A⁹ extend from the lower edge of the base and the upper edge of the ash-pit downward, partially inclosing the sides of the ash-pit. The ash-pit is provided with a door A¹⁰, 35 and the fire-pot is surrounded by a ring A¹², connected with the base by the posts A¹³. The surface of the upper part of the circular base is concaved and provided with an ornament consisting of a succession of oppositely- 40 curving cornucopias B so connected by foliated trailing stems B' as to form connecting parts of continuous waving vine-work encircling the stove. The stove-top has its middle horizontal division B² dome-shaped and 45 encircled by a decoration like that on the base, consisting of a succession of oppositely-curving cornucopias B³ so connected by foliated trailing stems B⁴ as to form connecting parts of continuous waving vine-work extend- 50 ing horizontally around the dome-shaped di-

vision. Beneath the middle dome-shaped division is a horizontal band B⁵ of scale scroll-work encircling the top. The legs have a central leaf ornament B⁶ and scroll ornament B⁷ on the opposite vertical sides. The ash-pit door is provided with a horizontal row of oval-shaped draft-openings C and honeysuckle ornaments C', the openings alternating with the ornaments. The lower door of the combustion-chamber is provided along its 55 lower part with a horizontal row of draft-openings D and on its upper part with a panel D', having the form of an arc of a circle, with a leaf ornament D² above and below each end of the panel. The upper door of the combustion-chamber is provided with a horizontal row of mica openings F along the middle of the door, each opening having a foliated border with a patera F' in each of the upper corners of the door.

What we claim as new is—

1. The design for a heating-stove herein shown and described, consisting of a cylindrical combustion-chamber having two contiguous doors, one above the other, an upwardly-flaring fire-box having a corrugated exterior surface extending entirely around the same, the corrugations extending vertically the whole length of the fire-box to a circular flange with plain unornamented surfaces, which separates the fire-box from the combustion-chamber, a dome surmounting the combustion-chamber, a circular base having its upper surface concaved, located beneath the fire-box, an ash-pit and legs partially inclosing the pit beneath the base, a ring inclosing the fire-box, and posts connecting the ring with the base.

2. In a design for heating-stoves, the design for an ash-pit door herein shown and described, consisting of a horizontal row of oval-shaped draft-openings and honeysuckle ornaments, the openings alternating with the ornaments.

3. In a design for heating-stoves, the design for a leg herein shown and described, consisting of a central leaf ornament and a scroll ornament on the opposite vertical sides.

4. In a design for heating-stoves, the design for a door herein shown and described, con-

sisting of a panel having the form of an arc of a circle, with a leaf ornament above and below each end of the panel.

5. In a design for a heating-stove, the design for a door herein shown and described, consisting of a horizontal row of draft-openings along the middle of the door, each opening having a foliated border, with a patera in each of the upper corners of the door.

10. 6. In a design for a heating-stove, the ornamental design for a base herein shown and described, consisting of a succession of oppositely-curving cornucopias so connected by foliated trailing stems as to form connecting parts of continuous waving vine-work.

15. 7. In a design for a heating-stove, the ornamental design for a top herein shown and described, consisting of a succession of oppositely-curving cornucopias so connected by foliated trailing stems as to form connecting parts of continuous waving vine-work extending horizontally around the dome-shaped middle division of the top, with a lower horizontal band of scale scroll-work encircling the top.

20. 25. In testimony whereof we have hereunto set our hands this 6th day of September, 1890.

H. CLAY BASCOM.
FRANCIS RITCHIE.
